PROTECTIVE MOUNTING FOR UNIFORM CAPS

Harry Lev, Chicago, Ill.

Application April 23, 1952, Serial No. 283,911

1 Claim. (Cl. 206—8)

This invention relates to a carton of paperboard or the like having therein a supporting mounting for a uniform cap which is thereby held in a fixed position where it is protected at all times and under all normal conditions of storage or shipment.

Uniform caps of the type for which the present carton has been designed are made with an endless frame of slightly oval contour and sufficiently resilient to comfortably conform with the head of the wearer. From such a frame a relatively stiff visor extends forwardly and downwardly at the front. A strap surrounds the frame in its lower portion and a flexible crown surmounts the frame to be supported at the front where the crown rises to a peak. This one support may or may not be yieldable, depending upon the construction that is used, but elsewhere the cap crown is extended laterally outwardly beyond the frame with freedom to droop through the rearward portion thereof. It is desirable that in storage or shipment the cap should be adequately protected so as to maintain its original contour, form and shape, and it is with a view to accomplishing this end that the present carton has been designed.

A suggestive embodiment of this invention is illustrated in the accompanying drawing wherein:

Figure 1 is a perspective view of the carton with a portion thereof broken away to show a uniform cap that is supported in a protected position therein;

Fig. 2 is a horizontal section through the carton, taken in a plane just below its top, the cap mounted within the carton being shown partly in plan and partly in horizontal section;

Fig. 3 is a vertical section, taken on line 3—3 of Fig. 2, and

Fig. 4 is a fragmentary detail in vertical section showing the platform in its operative relation to the carton bottom and one of its sides.

The carton which is desirably made of a suitable paperboard is formed with a substantially square bottom 5 from which upstands four sides 6. A top cover 7 is formed as an extension of one of the sides, and in its down position the cover is adapted to rest upon flanges 8 which are inturned from the remaining three sides at their tops. In all essential details the present carton may be of conventional construction so that further description thereof is unnecessary.

The uniform cap A for which such a carton is designed is of the type which comprises an endless frame F which is of slightly oval contour and around which is fitted a strap S. This frame is somewhat resilient so as to shape itself in conformity with the contour of the head on which it is worn. Extending forwardly and downwardly from the frame at its front is a relatively stiff visor V. A crown C surmounts the frame, and its front end is supported in any suitable way to provide a peak p which is of maximum elevation. The crown which is relatively flexible extends laterally and outwardly to provide an arcuate eave portion e which is disposed beyond the frame to the rear of the cap. The eave portion tends to droop down exteriorly

2

of the frame to overlie the upper portion thereof, particularly when not on the head of the wearer.

To protect such a cap, while stored or shipped, the present improvements have been designed. These comprise a substantially square platform 10 of paperboard or the like. This platform which extends close to each of the upstanding side walls of the carton is downturned at its margins to provide depending flanges 1. Owing to the resiliency which is inherent in the paperboard that should be chosen for the platform the flanges 11 tend to spring outwardly into frictional engagement with the carton walls 6. When operatively positioned within the carton, the bottom edges of these flanges rest on its bottom 5, so as to support the platform in a fixed position of elevation. The depending flanges 11 therefore provide a sustaining support for the platform when the carton is in its normal position with its open top uppermost, and also a frictional connection with the carton sides such as to hold the platform against displacement even when the carton is inverted.

A large opening 15 is provided in the platform. The contour of this opening is slightly oval with its long axis extending between two of the opposite corners of the carton. At its smaller end the opening is closer to the proximate corner of the platform than is the larger end of the opening to the platform corner that is proximate thereto (see Fig. 3). In general, the shape of the opening corresponds with the contour of the frame, but its size is slightly larger so that a space intervenes all around when the cap frame is fitted within the aperture.

In placing the cap within the carton for mounting upon the platform, the visor is first passed through the smaller end of the opening and the frame is then pressed inwardly, wherever necessary, to facilitate its movement through the opening. When done, the visor along its front edge will be rested upon the carton bottom 5 thereby to support the front end of the cap fixedly with its peak just below the top 7 of the carton (see Fig. 3). The crown eave portion e is engaged on its underside by the platform which provides a sustaining support therefor so as to prevent drooping thereof. When so supported, the cap frame F will also be lifted slightly off of the carton bottom 5 (see Fig. 3). The support for the cap crown thus furnished by the platform extends for a very substantial arcuate distance thereby distributing the cap weight widely over the platform. As a result there is no localized pressure tending to distort the platform or the cap crown and push it out of shape.

A uniform cap of the kind described when mounted within a carton having the features of this invention may be safely stored or shipped. Even when the carton is inverted, the cap will be held against shifting movement within the carton. This is due to the fact that the strap S is free to engage the underside of the platform 10 if the cap eave portion e should shift away from the platform. The same is true at the front end where the visor V will engage the underside of the platform 10 to prevent any extended upward movement of the cap at this point.

I claim:

1. The combination with a top-opening, four-sided, bottomed carton, of a rectangular cap-mounting platform of slightly resilient material arranged generally transversely within the carton, extending close to each of its sides, and provided with depending marginal flanges in frictional pressure engagement with the carton sides and in supporting engagement with the carton bottom, thereby to sustain the platform at a fixed distance between the carton top and bottom whether or not the carton be inverted, the platform being formed therethrough with only a single elliptical opening having its major axis extending diagonally between two of its opposite corners, the opening in the platform snugly receiving a uniform cap with its crown

portion above the platform and its peak at the front below the carton top and with its visor below the platform in supporting engagement at its front with the carton bottom in one corner portion thereof and in proximity to two adjacent carton sides thereby to be restrained from turning within its mounting on the platform, the opening occupying the major portion of the upper surface of said platform, and the platform providing a support of substantial extent for the drooping eave portion of the cap at its rear whereby to sustain the cap frame off of the carton bottom 10 and in spaced relation thereto.
